HORIZONTALLY SWINGING BARBER REST

Joe E. Bryan, Oather E. Bryan, and Van B. Crews, Plant City, Fla.; said Oather E. Bryan assignor to said J. E. Bryan and said Van B. Crews

Application August 5, 1947, Serial No. 766,210

2 Claims. (Cl. 155—81)

1

This invention relates to auxiliary seats and more particularly to an auxiliary seat for use with a barber's chair or other chair of a type in which persons are given treatments of one kind or another.

The invention is particularly concerned with a device on which a barber or other operator may conveniently sit when serving a customer, such as cutting his hair or performing some service.

Auxiliary seats for barbers and other chairs have been employed but they not been found completely satisfactory in all particulars, including simplicity of construction, manufacture, use, and ease of installation which are necessary for a practical, durable, and commercially feasible device.

It is therefore among the objects of the invention to provide a simple, inexpensive auxiliary seat for use by a barber or other workman serving a customer, which seat may be easily applied or removed and when installed can be easily adjusted to any desired location and with the seat mounted to rotate freely.

A further object of the invention is to provide an auxiliary seat which does not interfere in any way with the operation of the chair to which it is applied and which can be rotated completely about the chair with which it is associated.

Further objects and advantages of the invention will be apparent from the following description taken in conjunction with the accompanying drawings, wherein:

Fig. 1 is a perspective illustrating the application of the invention to a chair of the type in which persons are given treatment of one kind or another;

Fig. 2 an isometric view of the attaching collar;

Fig. 3, a vertical section through the attaching collar; and,

Fig. 4, a side elevation of the device applied to the base of a chair.

With continued reference to the drawings and particularly Fig. 1, a barber's chair is disclosed having a pedestal or base 10, a supporting column 11, adjustable therein for supporting a seat 12, an adjustable back 13 and an adjustable foot rest 14. A lever 15 controls the operation of the chair including the position of the back and foot rest.

The chair construction above described is conventional and is adapted to be used by barbers, dentists, and others who perform service for customers, patients and other persons. The required service is usually rendered by a barber or other person in a standing posture. However, excellent health is necessary in order to withstand the

2

rigorousness of the duties involved and the effort required could be reduced materially by the provision of a satisfactory seat for the operator.

In order to provide this seat, an adjustable attachment is applied around the base of the chair to which is secured an extension connected to an upright post, on the upper end of which is mounted a supporting seat.

On this seat a barber or other operator may sit during the performance of the desired services. Due to the fact that the seat is rotatable convenient access is afforded for any desired circumferential position.

The adjustable attachment around the base of the chair is in the form of a collar comprising a substantially cylindrical sleeve 16 formed of a pair of sleeve sections. This sleeve is provided with set screws 17 by means of which it may be applied to a supporting column or base 10, the set screws being adapted to make the sleeve applicable to columns of varying sizes.

About the sleeve 16, composed of the sleeve sections, are mounted a plurality of fixed hollow rings 18, 19 and 20, each formed of a pair of ring sections adapted to form a unit with the sleeve. In order to fasten the ring sections 18, 19 and 20 to the sleeve, the pair of ring sections 20 may be welded or otherwise permanently attached to the sleeve 16 and with the ends of such rings in the same general position as the ends of the sleeve. This permits one ring and sleeve section to be applied to each side of the column or post 10 and then the rings 18 and 19 secured to the ring 20 by means of bolts 21, a nut 22 serving to hold the parts in assembled relation.

Between the rings 18 and 19 is a spacing and bearing sleeve 23 which not only maintains the rings 18 and 19 in properly spaced relation but serves as a support about which the rollers 24 may rotate. In assembling the rings 18 and 19 the joints between the sections of the rings 18, 19 and 20 are preferably offset so that the parts can be held firmly assembled.

Adapted to rotate about the rollers 24 between the opposed faces of the rings 18 and 19 is a collar or ring formed of a plurality of ring sections 25 and a single ring section 26 having an attaching portion 27, all of which are fastened together in a unitary structure by means of bolts 28.

The combined thicknesses of a pair of the rings 25 and 26 is slightly less than the distance between the contiguous surfaces of the rings 18 and 19 so that the ring formed by the sections 25 and 26 can rotate freely about the rollers 24. The

primary difference between the rings 25 and 26 is that the ring 26 has an attaching portion 27 adapted to be secured by means of a bolt 29 in one end of a tube 30. Shims 30' on opposite sides of the attaching portion 27 serve to provide a solid connection with the tube due to the fact that the end of the tube is filled by such shims and the attaching portion 27.

The tube 30 telescopes into the end of the second tube 31 and is adapted to be adjustably fastened therein by means of a set screw 32. The opposite end of the tube 31 from the end that receives the tube 30 is provided with a right angular collar or sleeve portion 33 for receiving an upright or standard 34 adapted to be vertically adjustable therein but secured in fixed relation by means of a set screw 35.

On the lower end of the post 34 is fixed a yoke or substantially U-shaped member 36 provided with castors or anti-friction members 37 for engagement with the floor or supporting surface.

On the upper end of the upright or standard 34 is adjustably mounted a seat 38 on the under side of which is fastened a depending tube 39 having a concentric screw 40 therein.

The tube 39 is adapted to telescope over the upper end of the post 34, while the screw 40 threads in a fixed member or nut 41 in the standard so that by rotation of the seat 38 with the screw 40 the screw will thread through the fixed member or nut 41 and the seat will be vertically raised or lowered. Likewise, by the telescopic adjustment of the tube 30 in the tube 31 the distance of the seat from the supporting column or post 10 and the chair associated therewith will be determined.

With the construction described, hair and dust will be kept away from the rolls 24, free adjustment of the auxiliary seat about the main seat will be possible, and the device may be applied to supporting columns or posts which are not of the same diameter.

It will be obvious to those skilled in the art that various changes may be made in the invention without departing from the spirit and scope thereof and therefore the invention is not limited by that which is shown in the drawings and described in the specification, but only as indicated in the appended claims.

What is claimed is:

1. An auxiliary seat comprising a collar for attachment to the upright member of a chair of the character used by barbers, said collar comprising a pair of sleeve sections, set screws carried by said sleeve sections for engagement with the upright member of a chair to compensate

for variations in diameter of said member, a ring comprising sections permanently secured to the exterior of said sleeve, additional rings mounted on the first ring, spacer bearings mounted between said rings, means for attaching said additional rings to said first rings, said rings being arranged to define an annular channel about said sleeve, rollers rotatably disposed on said spaced bearings in spaced relation in said channel, a rotatable ring assembly about said rollers and comprising overlapping ring sections, an extension from one of said ring sections, an adjustable connection for said extension having a tubular sleeve at its outer extremity, a post vertically adjustable in said sleeve and having anti-friction surface engaging means at its lower extremity, a seat, a sleeve attached to said seat and telescoping over the upper end of said post, a screw carried by said seat, a fixed member carried by said post threadedly engaging said screw whereby rotation of the seat will cause raising and lowering of the same, said seat and associated collar means being freely rotatable about said chair.

2. In an auxiliary seat the combination of an upright, a seat on the upper end of said upright, anti-friction means on the lower end of said upright, a collar for attachment about the post of a barber's chair, said collar comprising a sleeve, a ring permanently attached to said sleeve, a pair of rings, means comprising spacer bearings for attaching said pair of rings to said ring and providing therebetween an annular channel, anti-friction bearing means disposed in said channel and rotatably mounted on said spacer bearings, a ring in said channel about said anti-friction bearing means, and an adjustable connection between said last named ring and said upright.
